US00D595746S

(12) **United States Design Patent**
Iida et al.

(10) **Patent No.:** **US D595,746 S**
(45) **Date of Patent:** **** Jul. 7, 2009**

(54) **FRONT LOADER**

(75) Inventors: **Tetsuya Iida**, Osaka (JP); **Yoshiaki Kuraya**, Osaka (JP); **Takumi Hasegawa**, Osaka (JP)

(73) Assignee: **Yanmar Co., Ltd.**, Osaka (JP)

(**) Term: **14 Years**

(21) Appl. No.: **29/324,791**

(22) Filed: **Sep. 19, 2008**

(51) LOC (9) Cl. **15-03**

(52) U.S. Cl. **D15/32; D15/28**

(58) **Field of Classification Search** **D15/10, D15/22-26, 28, 29, 32; 414/686, 694, 722, 414/718, 815, 723, 685; 37/341, 407**

See application file for complete search history.

(57) **CLAIM**

The ornamental design for a front loader, as shown and described.

DESCRIPTION

FIG. 1 is a front perspective view of a front loader showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is a right side perspective view of a front loader shown in use condition.

The features shown in broken lines depict environmental subject matter only and form no part of the claimed design.

1 Claim, 8 Drawing Sheets

FIG. 1

FIG. 2

FIG. 3

FIG. 4

FIG. 5

FIG. 6

FIG. 7

FIG. 8
